UNITED STATES PATENT OFFICE.

HARVEY I. LEIBY, OF BLOOMSBURG, PENNSYLVANIA.

PICKER BLOCK.

Application filed January 31, 1919. Serial No. 274,234.

To all whom it may concern:

Be it known that I, HARVEY I. LEIBY, citizen of the United States, residing at Bloomsburg, in the county of Columbia and State of Pennsylvania, have invented certain new and useful Improvements in Picker Blocks, of which the following is a specification.

This invention relates to picker blocks used on looms for weaving cloth or carpets, and has particular reference to an improvement therein which saves wear on the picker stop.

It is a well-known fact that the picker stick advances the picker block along the picker rod to throw the shuttle from the shuttle box and the forward movement of the picker block to discharge the shuttle from the shuttle box, is arrested in order that the picker stick, in returning to initial position may carry the picker block therewith. The ordinary means for arresting the movement of the block is a leather strap surrounding the picker rod, and since the movement thereof is very rapid to discharge the shuttle from the shuttle box at frequent intervals, the number of times it strikes the check or stop strap is very considerable. With the picker blocks now generally in use, this strap becomes rapidly worn by the action of the head of the picker block striking thereagainst. That is to say, owing to the fact that said head is of relatively small diameter, and made of relatively hard material, such as rawhide, it quickly penetrates or wears away the strap, thereby rendering it necessary for a new portion thereof to be brought into place while the old part must be cut off and discarded. Obviously, this rapid destruction of parts or sections of the check strap involves considerable waste in material and also causes the loss of much valuable time in operating the loom.

Accordingly, the present invention has primarily in view a picker block construction wherein the head or portion surrounding the picker rod is of considerably enlarged diameter, thus presenting a relatively large impact end, whereby, when the picker block strikes the check strap under the action of the picker stick, the area of impact will be comparatively large which will have a tendency to eliminate concentrated wear on the check strap where it surrounds the picker rod and thus prolong the

life of the check strap. That is to say, the present invention has primarily in view the provision of a picker block having an enlarged bumper head whereby the impact of the blow against the check strap will be distributed over a greater surface and thus wear the strap evenly throughout the area of contact.

A further object of the invention is to make the bumper head portion of the picker block of such a size that the relatively flat body portion of the picker block will not come into contact with the check strap, and thus prevent the portion of the strap between the opening for the picker rod and the edge from being rapidly worn out as has been the case heretofore.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a perspective view of the improved picker block, showing the buffer strap and the spindle rod in dotted lines engaging in one of the openings in the strap.

Figure 2 is an end elevation of the picker block shown in Figure 1.

Figure 3 is an end elevation of a picker block showing a slightly modified shape of bumper head.

Figure 4 is a detail side elevation illustrating the manner in which the buffer strap is threaded on the spindle rod.

Like reference characters designate corresponding parts throughout the several figures of the drawings.

In carrying the present invention into effect it is proposed to follow the general design of picker blocks now in use, and therefore as will be observed from Figure 1 the present block includes a suitable flat body web 1 having at one side thereof the usual shuttle engaging portion 2 while the opposite side thereof is provided with the enlarged bumper head portion, the same having the axially disposed opening 4 for receiving the picker rod in the usual well known manner. The said body of the picker block is also provided with the picker stick receiving opening 5 which because of the

relatively large diameter of the bumper head portion 3 is located within the central part of the enlargement 3. This enlargement 3 is cut-away as indicated at 5^a to expose the central portion of the opening 4 thereby to permit the picker rod to be oiled at the center of the picker block and thereby prevent oil from being thrown off from the ends thereof onto the fabric. The fact that 10 the picker stick opening comes within the zone of the enlarged bumper head demonstrates the relatively great diameter of the latter and emphasizes the primary and distinctive feature of the present picker block, 15 namely, that of providing a head portion for the block which is of such a large diameter that it provides end impact faces 6 of relatively large area for engaging with the check strap S shown in Figure 1.

20 The said check strap S is usually made in lengths of about eighteen inches long and two inches in width and has holes punched therein at regular intervals, whereby the picker rod may be threaded through any of 25 the holes which register when the strap is looped thereon as shown in Figure 4. According to the prior practice this check strap becomes rapidly worn out directly around the picker rod opening owing to the relatively small and sharp character of the end 30 portion of the ordinary picker block. Furthermore, the edge of the strap when used with the old style picker block becomes worn out or cut away which necessitates the operator of the loom stopping his machinery, 35 removing the strap from the rod, and bringing a new portion thereof into play. If the worn strap is left in place the picker block will not throw the shuttle correctly, thus 40 causing a break in the weaving operation which often results in serious damage, and always in flaws. These conditions cannot prevail with the type of picker block shown 45 in the drawings and above described, because of the fact that the enlarged bumper head portion 3 provides an impact end of relatively large diameter, which diameter is substantially the width of the check strap. Thus the impact of each blow of the picker 50 block against the strap is distributed over the entire surface of the strap surrounding the hole through which the picker rod

passes. The enlarged diameter of the bumper head is sufficient to embrace the edge of the body of the picker block which would otherwise strike against the relatively small edge of the check strap and thus rapidly cut it away as happens in the case of the old block.

55 In the form of the invention shown in 60 Figures 1 and 2 the bumper head portion 3 of the block is preferably shown round, so that it will strike the check strap S over the area indicated by dotted lines in Figure 1, but it will of course be understood that 65 equally effective results may be obtained with the square head shown in Figure 3 of the drawings. Any suitable material may be utilized in making the present picker block such for instance as rawhide, leather, vul- 70 canized fibre, or equivalent material.

75 From the foregoing it will be apparent that the primary feature and distinguishing characteristic of the present invention is the provision of a picker block having an en- 80 larged bumper head portion whereby the end or ends of the head will constitute impact surfaces of relatively large or increased area, in contra-distinction to the relatively small diameter or ring-like end of the ordinary picker block.

I claim:

1. A picker block for looms including a bumper member having openings respectively for the picker rod and the picker 85 stick and being cut away to expose a portion of the opening for the picker rod.

2. A picker block for looms including a bumper member having an opening for the picker rod and the intermediate portion 90 thereof being cut-away to expose a portion of said opening, and the said member also being provided with a slot at one side of the exposed opening to accommodate the picker stick while the end walls of said member 95 are substantially the same length as the width of the surface against which such ends impact.

In testimony whereof I hereunto affix my signature in the presence of two witnesses. 100
HARVEY I. LEIBY.
